UNITED STATES PATENT OFFICE

JAMES O. LEWIS, OF TULSA, OKLAHOMA, ASSIGNOR, BY MESNE ASSIGNMENTS, TO DUNN & LEWIS, OF TULSA, OKLAHOMA, A PARTNERSHIP COMPOSED OF IRWIN L. DUNN AND JAMES O. LEWIS

METHOD OF REPRESSURING OIL SANDS

Application filed November 22, 1928. Serial No. 149,979.

My invention relates to a method of repressuring oil sands and more particularly to the replacement of gases with atmospheric air for maintaining a proper volume of pressure medium without danger of explosion resulting from compression and ignition of these elements of the pressure medium.

It is a common practice in those fields where the initial rock pressure has become exhausted or so depleted as to be insufficient for forcing liquid petroleum from the sands into the producing wells to supply an artificial pressure for that purpose. The artificial pressure medium originally consisting of air or natural gas is forced into a central well of a group under sufficient pressure to move the liquid petroleum ahead of it through the sands into producing wells, the pressure medium then being recovered for re-use and the hydrocarbon content accumulated during travel of the medium through the sands being removed by condensation or otherwise. With a system of this kind it is customary to draw off a part of the gases for use as fuel in the explosion engine which operates the compressor and to replenish the supply of circulating gases with fresh air. When the fresh air is mixed with the gases it forms a combustible mixture which not infrequently becomes ignited from back-fire of the engine, lightning or other causes, resulting in explosions which cause damage to the equipment and injury to workmen.

The principal object of the present invention is to obviate this danger of explosion by supplying the pressure medium in separate slugs of air and gas which are respectively too lean or too rich for ignition and may consequently be employed without danger of explosion.

In accomplishing this object I employ improved details of structure, the preferred forms of which are illustrated in the accompanying drawings, wherein:

Fig. 1 is a perspective view of an apparatus with which my improved method may be employed.

Fig. 2 is an enlarged vertical section of the gas trap and air and gas valve included as elements of the apparatus.

Fig. 3 is a longitudinal sectional view of the air and gas valve and a part of its operating lever.

Referring first to the apparatus by reference to the drawings:

1 designates an air well, i. e. the central well in a group to which artificial pressure medium is supplied for feeding the other or producing wells 2. Located in suitable proximity to the wells is a compressor 3 of portable or stationary type comprising high and low stage chambers 4 and 5 and pistons (not shown) operable from an explosion engine indicated by the cylinders 6 and 7 and a mixing chamber 8.

Opening from the producing wells 2 are branches 9 connecting with a main return line 10 leading into the lower portion of a tank 11 adjacent the compressor and upturned at the center of the tank to about the middle thereof and there terminating in a return bend 12.

Leading through the lower portion of the tank 11 is a conduit 13 also extending centrally through the tank to about the middle thereof and terminating in a return bend 14, the conduit 13 having a branch 15 exterior to the tank, opening to atmosphere and having a three-way valve 16 between the branch and tank. Opening from the valve 16 is a pipe 17 leading to the low stage compressor cylinder 4. The stem 18 of the valve 16 carries a lever 19, having a lip 20 on its free end provided with an aperture 21. Extending loosely through the aperture 21 is a rope 22 which extends over pulleys or guide rollers 23 suspended from a beam 24 on a frame 25 enclosing the tank 11 and thence centrally through the top of the tank.

Suspended from the rope 22 within the tank is a bell 26 enclosing the gas conduits 10 and 13 and their return bends, the bell extending to near the bottom of the tank and the tank and cylinder containing a sealing liquid 27 having a level slightly below the mouths of the return bends of the gas conduits. Fastened to the rope 22 above the valve lever 19 is a weight 28 for counterbalancing the bell 26 and for engaging with the valve lever to rock the latter when the bell is elevated by a volume of gas flowing thereinto from the 100

producing wells. Below the valve lever the rope 22 is provided with a button 29 for engaging and rocking the lever when the bell descends following escape of gas from its interior. With this arrangement gas admitted to the bell raises the latter until the weight 28 shifts the valve lever in the conduit leading to the compressor, opening the conduit to the passage of gas admitted from the bell through the return bend in pipe 13. As gas escapes from the bell, the latter descends by gravity lifting the button on the end of the rope 22 until the latter engages the valve lever, shifting the lever to close off the gas supply and admit air to the pipe 17 through the branch 15. It is apparent, therefore, that gas and air are admitted to the compressor separately and not in such relation as to produce a combustible mixture.

20 The low stage compressor cylinder 4 is connected with a high stage cylinder 5 by a pipe 30 and leading from the high stage cylinder is a pipe 31, coiled at 32 to form a condenser and communicating with a scrubber tank 33 wherein condensable content of the compressed fluid is collected. Opening from the top of the tank 33 is the pipe 34 which leads to the air well 1.

Opening from the pipe 13 between the tank 30 11 and three-way valve 16 is a branch 35 leading to the mixer 8 of the gas engine for supplying gas returned from the wells to the engine for use as a fuel therein.

In practicing my improved method with the aid of the apparatus described, assuming the apparatus to be assembled and connected with the wells as above stated, when the engine is in operation air is initially drawn through the low stage cylinder, compressed therein and in the high stage cylinder and passed through the pipe 31, tank 33 and pipe 34 to the air well in the field. The air being forced through the sands drives the liquid along with it to the producing wells 45 from which the oil may be recovered in accordance with common practice. As the air travels through the sand it becomes saturated with lighter constituents of the petroleum contained within the sand so that when it leaves the producing wells it constitutes a combustible vapor or saturated gas. When this vapor or gas is delivered to the bell of the gas trap it accumulates therein until its pressure is sufficient to lift the bell and shift the valve in the compressor supply conduit. When the valve is shifted the air supplied to the compressor is cut off and the gas supply opened, the gas and vapor then passing from the bell into the compressor and from there 50 circulated to the air well, as was the atmospheric air heretofore mentioned. As the gas escapes from the bell the latter descends by gravity until the three-way valve is again shifted, when the gas supply is shut off and the air supply again opened. In this way

alternate charges of gas and air are separately admitted to the compressor and delivered in separate slugs into the air well, at no time co-mingling to produce a combustible or explosive mixture.

In this way, I am enabled to employ air and gas for use as artificial pressure medium in the stimulation of flow of inert oil from the sands and increase or renew production in fields which have been abandoned or have decreased in production to such an extent as to be unprofitable.

What I claim and desire to secure by Letters Patent is:

1. The method of repressuring oil sands consisting of delivering charges of air and gas alternately to the sands under pressure. 80
  2. The method of repressuring oil sands consisting of delivering charges of air and gas alternately to the sands through the same line under pressure. 85
  3. The method of repressuring oil sands consisting of delivering a continuous flow of pressure medium consisting of alternate volumes of air and gas to the sands. 90
  4. The method of repressuring oil sands consisting of compressing air and gas separately and delivering the air and gas to the sands under pressure in alternate volumes and in continuous flow. 95
  5. The method of repressuring oil sands consisting of supplying gas and air alternately to a compressor, compressing the gas and air separately in the compressor and supplying the compressed gas and air to the sands. 100
  6. The method of repressuring oil sands consisting of storing gas, admitting said gas and air alternately to a compressor, compressing the medium admitted to the compressor, delivering the medium under pressure to the sands, and controlling selection of the medium to be compressed by volume of the stored gas. 105
  7. The method of repressuring oil sands consisting of supplying gas and air alternately to a compressor, compressing the medium supplied to the compressor, delivering said medium to the sands, and controlling selection of the medium supplied to the compressor by volume of the gas available at the point of supply. 110
  8. The method of repressuring oil sands consisting of recovering and confining gas from a producing well, supplying said gas and air alternately to a compressor, compressing the medium supplied to the compressor, delivering said medium to the sands under pressure, and effecting selection of admission of gas or air to the compressor according to volume of the confined gas. 115
- In testimony whereof I affix my signature.

JAMES O. LEWIS.
